PRESSURE-RESPONSIVE DEVICE

Herman Schaevitz, Collingswood, N. J.

Application June 19, 1947, Serial No. 755,561

3 Claims. (Cl. 137—786)

1

This invention relates to pressure-responsive devices and more particularly to a novel device of this character which is adapted to be operated by fluid pressure and which is substantially unaffected by temperature changes.

A common form of fluid pressure-responsive devices is one which employs a bellows member or the like wherein the fluid pressure acts on a diaphragm at one end of said member to move the diaphragm against the resisting action of the bellows. Where differential pressures are involved, two opposed bellows may be interconnected and may be subjected to the different pressures respectively. Prior devices such as those mentioned, are generally subject to the objection that they tend to be actuated undesirably by ambient temperature changes and/or changes of temperature of the fluid.

One object of the present invention is to provide a device which is responsive only to pressure variations and is substantially immune to temperature variations.

Another object of the invention is to provide such a device of simple construction and which may be manufactured easily and economically.

Other objects of the invention will be apparent from the following detailed description.

In the accompanying drawing,

Fig. 1 is a longitudinal sectional view of a device constructed according to the present invention;

Fig. 2 is a transverse sectional view taken along line 2—2 of Fig. 1; and

Fig. 3 is a view, partly in elevation and partly in section, showing the application of the device for a different purpose than that illustrated in Fig. 1.

Referring first to Figs. 1 and 2, in the form of the device illustrated there is provided a cup-shaped member 1 and an associated inclosure member 2 threadedly secured to member 1 as at 3. The two members 1 and 2 form a fluid chamber 4 to which fluid under pressure may be supplied through the tubular extension 5 on member 1, said extension having threads 6 for attachment to a conduit or other means through which the pressurized fluid may be transmitted from a suitable source. The member 2, which constitutes a wall of chamber 4, is centrally apertured to accommodate the elements now to be described.

A pair of bellows members 7 and 8 have extended end portions 9 and 10 respectively which extend into the aperture of wall 2 and are supported by said wall, e. g. by a retaining ring 11 and by being soldered or otherwise secured to the wall. The wall 2 is of increased thickness about

2

the aperture therein to provide a relatively wide circular portion 12 which cooperates with the ring 11 to retain the end portions of the bellows members. It will be noted that the bellows member 7 extends exteriorly of the chamber 4 while the bellows member 8 extends interiorly of said chamber. The bellows member 7 has a closed end 13 constituting a diaphragm, while the bellows member 8 has a generally similar end portion 14 which however, is apertured to admit the pressurized fluid into the otherwise closed chamber 15 formed by the two bellows members. As shown in Fig. 2, the diaphragm 14 preferably has a plurality of circularly arranged openings 16 so as to freely admit the pressurized fluid to the chamber 15. The two opposed diaphragms 13 and 14 are interconnected by a rigid member 17 extending axially of the chamber 15. The member 17 may be in the form of a metal rod which is substantially unaffected by any temperature changes that may be expected to occur. It is to be understood however, that the said member may be formed of any suitable material other than metal.

25 It will be seen from the description thus far, that the pressurized fluid is supplied to the chamber 15 within the bellows members, and such fluid is also applied to the exterior of the bellows member 8 within the compartment 4. Hence it 30 will be seen that the head or diaphragm 13 of bellows 7 will be moved by the fluid pressure against the resisting action of both bellows members. Thus when the fluid pressure increases, the diaphragm 13 is moved toward the left 35 against the tensional resistance of bellows 7 and against the compressional resistance of bellows 8. The interconnected opposed bellows members may be likened to two springs and these two members effectively provide a double restoring force for the diaphragm 13. Any change in ambient temperature or in the temperature of the fluid will have no effect upon the diaphragm 13 due to the rigid connection between it and the opposing diaphragm 14. Consequently, the diaphragm 45 13 will be moved only by pressure variations of the fluid supplied to the device.

The movement of the diaphragm 13 in response to pressure variations may be utilized for any desired purpose. In Fig. 1 there is shown an electrical pick-up which may be utilized to indicate the movements or position of diaphragm 13 by converting them to corresponding magnitudes of self inductance or mutual inductance. As illustrated, the electrical pick-up comprises a plurality of coils 18 wound on a support 19 which

is secured to the wall member 2 by means of suitable fastening elements 20. A magnetic core 21 is mounted on the extended end of member 17 and is movable within the coils 18 to create a varying magnetic field. A cover 22 serves to enclose the pick-up device and the bellows 7, the said cover being engaged with the member 2. Wires which would be necessary to supply power to the coils and to carry the signals from the coils to the electrical indicator or controller are not shown since the necessity for these connections is understood by those familiar with the art.

Fig. 3 is intended merely to show that the device of this invention is applicable to a wide variety of uses. As illustrated, the device may serve to actuate an indicating device comprising a dial 23 and a pointer 24. The device of the present invention is represented generally at 25 and it serves to actuate a gear sector 26 which meshes with a pinion 27 within the indicating device. In this instance, the member 17 is extended and is connected to the gear sector 26 by means of a link 28. Thus the device of this invention may serve as part of a pressure gauge which also includes the dial indicator shown in Fig. 3.

From the illustration of Fig. 1 it will be seen that the device provided according to the invention is extremely simple in construction, and the parts thereof may be produced at low cost and may be easily assembled. Thus the invention provides a simple pressure-responsive device which is substantially immune to temperature variations and which also has the double restoring action above mentioned.

It is to be understood, of course, that the invention is not limited to the specific structure shown and furthermore it is applicable to any use where it is desired to translate pressure variations into mechanical movements for any desired purpose.

I claim:

1. A pressure-responsive device, comprising a pair of opposed expandible and contractible members having substantial tensional and compressional resistance and constructed and arranged to form a chamber, one of said members having at least one unrestricted opening therein to admit fluid freely to said chamber, means for supplying fluid under pressure to said opening and for applying such fluid to both sides of said one member, said chamber being closed to fluids other than the aforementioned fluid, and a rigid connection between the ends of said members, whereby the end of the other member is movable by the fluid pressure applied only to its interior against the resisting action of both members and

is substantially unaffected by changes in ambient temperature or changes in the temperature of said fluid.

5 2. A pressure-responsive device, comprising a fluid chamber, means for supplying fluid under pressure to said chamber, said chamber having an opening in a wall thereof, a first resistive bellows member extending from said wall exteriorly of said chamber and being closed at its 10 end, a second resistive bellows member extending from said wall interiorly of said chamber and forming with said first bellows member an auxiliary chamber which extends through said opening, said second bellows member having openings 15 in its end through which said auxiliary chamber freely communicates with said first chamber, said chambers being closed to fluids other than the aforementioned fluid, and a rigid connection between the ends of said bellows 20 members whereby the closed end of said first bellows member is movable in response to the pressure of said fluid against the resisting action of both of said bellows members and is substantially unaffected by changes in ambient temperature or 25 changes in the temperature of said fluid.

3. A pressure-responsive device, comprising a generally cylindrical member forming a chamber and fixedly supported centrally of its ends and the oppositely-extending halves of which are 30 longitudinally expandible and contractible and having substantial tensional and compressional resistance, said chamber having at least one unrestricted opening to admit freely fluid under pressure, means for supplying fluid under pressure to said chamber through said opening and for applying such fluid to the exterior surfaces of the half of the member containing said opening, said chamber being closed to fluids other than the aforementioned fluid, and a rigid connection 35 between the ends of said member, whereby the end of the closed half of said member is movable by the fluid pressure applied only to its interior surface and is substantially unaffected by changes in ambient temperature or changes in the temperature of said fluid.
